UNITED STATES PATENT OFFICE.

ROLAND CHILTON AND ALEXANDER H. KING, OF KEYPORT, NEW JERSEY, ASSIGNEES
TO AEROMARINE PLANE & MOTOR COMPANY, A CORPORATION OF NEW YORK.

RELEASING DEVICE.

Application filed November 23, 1922. Serial No. 302,763.

To all whom it may concern:

Be it known that we, ROLAND CHILTON, a subject of the King of England, and ALEXANDER H. KING, a citizen of the United States, and both residents of Keyport, in the county of Monmouth and State of New Jersey, have invented certain new and useful Improvements in Releasing Devices, of which the following is a specification, reference being had to the accompanying drawings, forming part of this specification.

This invention relates to devices of general application wherever it is desired to transmit movement from a driving to a driven member and the invention specifically relates to an improvement in releasing devices in which the driving member is maintained in operative driving relation with the driven member only under normal conditions.

The present embodiment and its specific application as herewith illustrated, constitutes a manually operated starting device detachably connected to the shaft of an internal combustion engine by which the engine is started or "turned over" manually, although it is obvious that the embodiment as shown and described can be made applicable to driving connections other than those manually operated by only slight modifications therein and without departing from the spirit of the invention.

The present invention constitutes an improvement over the disclosure in the application of Roland Chilton, 500,805 filed September 15, 1921, in which a frictional engaging clutch with inertia control was disclosed. In the present application there is featured a positive or non-frictional driving means which is also inertially disengaged or demeshed.

For certain requirements the frictional engagement is objectionable on account of the relatively large diameter of the clutching elements necessary to afford adequate frictional grip, and in such cases the positive engagement between the driving and driven member which is featured in the present disclosure is of advantage in that the mechanism can be disposed in a much smaller space. For instance, an automatic releasing device according to the present disclosure can be located at the hub or center of a hand starting crank without causing

a cumbersome structure which location 55 would not be practicable in the case where the relatively large friction members were used.

In devices of the class here contemplated, a release between driven and the driving member is effected under full load and where square trip faces of the prior art are used to accomplish a release, rapid wear is bound to develop. It will be understood that as one trip face is moved across its 60 companion towards the disengaging point the areas in contact are continuously decreasing until at the instant of release or just as the corners of the trip surfaces disengage the intensity of pressure becomes 65 extremely high.

One of the objects therefore of this invention is to provide a trip mechanism which will release under full load conditions and wherein the intensity of pressure 75 between the tripping parts will remain at a constant and moderate figure throughout the whole tripping movement up to and including the instant of release. We attain this object of the invention by interposing a 80 roller between the trip faces so proportioned as to be capable of sustaining the loads involved without distress.

In the previous art there are many devices whereby it is attempted to restrain the 85 backward rotation of the driving means by a ratchet or other one way device rigidly anchored against reverse rotation. Such rigidly anchored devices for positively preventing reverse rotation of the hand crank 90 have also been used to actuate releasing devices for severing the driving connection between the cranking means and the engine. Any such device is open to the objection that the releasing means must come into contact 95 with the fixed element before the releasing action is initiated. But instantly this contact with the fixed means is established, the full force of the back fire is imposed upon the whole mechanism which then forcibly 100 restrains the engine from reverse rotation until the demeshing movement is complete.

It should be understood that the reverse rotation of the engine under a back fire is extremely violent, so much so that the inertia of the crank handle alone is often sufficient to fracture the mechanism when a back fire occurs. This condition is espe-

cially troublesome in connection with aircraft engines for which geared up cranking means must be employed which greatly increases the effective inertia of the parts 5 and which necessarily includes in the system gears and their bearings and housing which constitute an additional liability to breakage.

Further, in connection with aircraft engines, the crank handle is generally required 10 to be detachable and owing to the relative light character of the fuselage or other airplane structure wherefrom the crank shaft issues from the machine to receive the handle, no sufficiently strong anchorage for a fixed member for forcibly restraining reverse rotation is available. An object of 15 this invention is to afford a back fire releasing device which will be independent of fixed abutments and which may accordingly 20 be incorporated entirely upon a detachable cranking handle.

The prior art also shows back fire devices 25 wherein it is necessary to effect some manual adjustment of the parts in order to bring them into re-engaged position following on a back fire. It is another object of the present invention to secure a device wherein the mere rotation of the crank will 30 automatically bring the parts of the re-engaged relation, and which will at the same time have means to positively prevent the re-engagement of the parts during the reverse rotation of the cranking shaft which 35 follows on a back fire.

Still another object of the construction is to reduce the friction encountered in carrying out the demeshing or tripping movement. As will be seen later this is important 40 in connection with the device like the one of the showing where only a relatively small force is conveniently available for carrying out the demeshing movement.

A further object of this invention is to 45 provide a simple form of construction in which a normally operative driving connection is promptly, positively and automatically intercepted upon any tendency of the driven member to be reversed or even 50 decelerated in speed while turning forwardly.

A still further object of this invention is to provide a means that will not only 55 disengage upon a back fire or other shock to the driven mechanism but that will stay out of engagement until reverse rotation of the driven member following on such back fire has substantially ceased.

This invention contemplates the utilization 60 of a clutching mechanism including a driving member and a driven member in which the clutching connection is normally maintained by a spring tending to hold the parts in their usual driving relation and in 65 which an inertially controlled member

moves a latch or pawl member into inoperative position automatically on a reversal in movement of the driven member.

Various other objects and advantages of the invention will be in part obvious from 70 an inspection of the accompanying drawings and a careful consideration of the following particular description and claims of one form of mechanism embodying our invention. 75

In the drawings:

Figure 1 is a rear elevational view of our invention illustrating the preferred embodiment and showing the elements in a normal or clutching position; parts are broken 80 away for the sake of clearness.

Figure 2 is a side elevational view partly in section, said section being taken on the line 2-2 of Fig. 1 looking in the direction indicated by the arrow. 85

Figure 3 is a rear elevational view showing the elements in a released or declutched position.

Figure 4 is a fragmentary view on a larger scale than Figs. 1 and 2 showing the elements in the act of declutching or releasing. 90

Figure 5 is a fragmentary view on the same scale as Figs. 1 and 2 showing some of the elements transposed so as to permit of the mechanism being used for rotation in a counter direction of that shown in Fig. 1. 95

With reference to Figs. 1 and 2, 10 designates the end of a starting shaft, suitably connected to the engine to be started (not shown), 11 denotes in general what hereinafter will be more specifically referred to as the driving member. To one end an arm 12 of the driving member 11 there is connected a handle 13 and at the other end thereof is formed integral therewith a hollow cylindrical body portion 14 having a sleeve or bearing 15. What will be herein-after specifically referred to as the driven member is a disk member 24 having an integral journal portion 16 rotatably mounted in the bearing 15 and secured against axial movement thereon by the screw 17 and the shoulder 18. An also integral enlarged sleeve portion 19 is adapted to fit upon the end of the starting shaft 10 and having a driving relation therewith by means of a pin 21 secured in the shaft 10, said pin engaging the slot 22 of the sleeve 19. 110

The disk is housed within the body 14 of the driving member 11 and is concentric therewith. 115

In a reinforced portion 26 of the disk 24 and on the periphery thereof there is formed an elongated notch 27 having conveniently 120 rounded inner corners 28. Upon the disk 24 there is secured by means of a screw 29 and a pin 31, a bent spring 32, and rotatably mounted thereon is a roller 33 of approximately the same diameter as the depth of 125

the notch 27 and of such length as to conform with the thickness in cross section of the reinforced portion 26. The roller 33 is disposed within the notch 27 in a manner 5 so as to permit of it being operated therein as will be more fully described hereinafter.

Upon a stud 34 secured in the driving member 11 there is mounted in an oscillatory manner a member 36 having an upwardly 10 extending off-set lever 37 terminating into a relatively massive weight 38. The lower portion of the member 36 comprises two outwardly and downwardly extending arms 39 and 41 connecting with an integral and 15 also relatively massive weight 42, thus forming an opening 43 through which the sleeve 19 projects; the bosses 44 acting as stops for the member 36 to limit the movement thereof.

20 Mounted on the stud 34 and secured to the arm 41 by means of a screw 45 is a latch or pawl 46 adapted to engage the roller and thereby the notch 27 and to be held in effective relation therewith by a spring 47 bearing against the pawl 46. It is important 25 that the driving effort on the pawl 46 should have no reaction tending to move this member either into or out of operative engagement. To this end then the operative 30 driving face 48 of the pawl which engages the roller and the corresponding driving face 49 of the slot 27 in the disk 24 are made as portions of arcs concentric with the pin 34.

35 The weight 42 is of such mass as to provide a counter-balance for the weight 38 to prevent the pawl 46 being released due to the effect of gravity or centrifugal force acting on the weight 38 when in certain positions, while the driving member is being rotated.

In operation and first considering the normal positions of the members as shown in Fig. 1, it will be understood that the tension 45 of the spring 47 is such as to maintain the pawl 46 in operative or clutching engagement in the notch 27 of the disk 24, with the roller 33 when the driving member 11 is moved in a counter clockwise direction, with 50 reference to the aspect of Fig. 1 as indicated by the arrows. This starting operation of the driving member 11, or in fact any acceleration thereof will result in the inertia of the weights 38 and 42 causing them to lag in 55 their movement and adding to the pressure of the spring 47 in maintaining the pawl 46 in a clutching position. The disk 24 will thus be rotated with the arm 12 through the intermediary of the pawl 46 and the roller 33 60 and will in turn rotate the shaft 10 by means of the pin and slot connection in the sleeve 19.

In the event of the driven mechanism decelerating its speed or suddenly reversing 65 its rotation for reasons such as a back fire

of the engine connected to the driven member by means of the shaft 10, the active inertia or momentum of the weights would oppose such deceleration or reversal of rotation and cause the lever 37 to move against 70 the tension of the spring 47 and thereby disengage the pawl 46 from the disk 24 as shown in Fig. 3, and permit the disk to spin around with the shaft without affecting the driving member which would remain at rest 75 or continue on in its initial direction. While the disk is being thus idly rotated in this manner, the pawl 46 bears against the periphery thereof, but due to the speed of rotation of said disk the pawl will jump the gap 80 and not engage the roller. To this end the circumferential length of the notch 27 and the shape of the end of the pawl 46 are proportioned so that the pawl will only fall into the slot and re-engage the roller when 85 the relative speed of movement between the hand crank and the disk 24 is low. In order to re-engage the pawl after it is released the hand crank is rotated slowly, the driven disk 24 being then at rest, and as soon as the pawl 90 gets into line with the slot 27 re-engagement will be effected by the spring 47. Such re-engagement cannot occur while the driven disk 24 is rotating backwards with any considerable velocity such as occurs following 95 on a back fire but as the disk 24 slows down in its reversed movement caused by the back fire to a relatively slow speed such remeshing can occur, and the parts will then be in driving relation provided the remeshing occurs without violence. The strength of the 100 spring 47 and the mass of the weight 38 are so proportioned that the spring is only capable of accelerating the weight 38 relatively slowly, therefore the riding of the pawl over the slot is assured, except at extremely low 105 relative speed.

It will be seen that immediately after disengagement due to back fire the starting drive shaft 10 will be rotating backwards at high speed and that serious damage to the parts or the operator would ensue should the driving connection remesh before the driven shaft has ceased to rotate backwards.

Referring to Fig. 4 the pawl 46 is shown 110 in the act of releasing or declutching from its normal driving position as bearing against the roller 33. It will be noticed that the areas of contact due to the contour of the engaging parts and the outward movement of the roller remain approximately constant throughout the whole tripping movement up to and including the instant of release, also that the roller partly facilitates the releasing of the pawl by reducing the friction at this point.

Referring to Fig. 5 the pawl 46 and the roller 33 are shown in a transposed position from that shown in Fig. 1. When it 120 becomes desirable to convert the driving 125

member from operating in a counter clockwise direction to a clockwise direction the above mentioned parts can be readily connected as shown.

5 It is to be noted that the reversal of rotation of the shaft 10 due to a back fire is relatively violent consisting of a very sudden and powerful jerk on the driven member causing oftentimes serious injury to the operator when the driving member is manually operated without automatic releasing means. It is possible with a device of the character disclosed to positively effect an instantaneous disengagement of the driving connection automatically and without any tendency to transmitting the reversed torque of the driven member to the driving member. The driving connection not only becomes promptly inoperative at the first disposition 20 of the driven member to reverse but also acts promptly even on a deceleration of its speed.

Variations may be resorted to within the scope of the invention and portions of the improvement may be used without others whilst not departing from the spirit of the invention.

Having thus described our invention, we claim:—

30 1. In a device of the character described, the combination of a driving member, a driven member, a normally operative driving connection comprising a latch associated with the driving member and adapted to engage the driven member by means of an interposed anti-friction roller, means for maintaining the driving connection in an operative position, means for supporting the roller in operative relation with said driving connection, and means adapted to become operative when the rotation of the driven member becomes opposed to that of the driving member to cause said driving connection to become ineffective.

45 2. In a device of the character described, the combination of a driving member, a driven member, a pawl a roller and a notch coacting to form a driving connection between the driving and the driven members and a weighted lever operatively connected to the pawl to control the same.

55 3. In a device of the character described, the combination of a driving member, a driven member, a normally operative driving connection therebetween comprising a pawl carried by the driving member and engaging the driven member, a spring acting on the pawl under normal conditions to maintain said pawl in an effective position, 60 a roller for said pawl to bear against and a weighted lever carried by the driving member adapted to move said pawl into an ineffective position under abnormal conditions.

65 4. In a device of the character described,

the combination of a driving member, a driven member, a pawl associated with the driving member and engaging the driven member in a manner so as to normally form a driving connection therebetween, means 70 for actuating said pawl into a released position, and a roller on a driven member interposed between the pawl and said driven member adapted to minimize the friction between the pawl and the driven member when 75 said pawl is being released.

5. In a device of the character described, the combination of a driving and a driven member, a pawl mounted on the driving member, a notch in the driven member, a resilient member carried by the driven member and having a roller mounted thereon, said roller disposed within said notch, a resilient member carried by the driving member adapted to maintain the pawl in an engaged position in the notch and against said roller under normal operating conditions and a weighted lever pivotally mounted in manner so as to effect a release of the pawl under abnormal conditions.

6. In a device for starting engines and the like, the combination of a driving member, a driven member, a positive driving connection therebetween operatively engaging the driven member and adapted to be moved to a disengaged position, driving surfaces on the driving connection and the driven members so constituted that the areas in contact of said driving surfaces will remain approximately constant while the driving connection is moving towards the disengaged position.

7. In a device for starting engines and the like, the combination of a driving member, a driven member, a normally effective positive driving connection comprising a latch therebetween, an interposed element associated with the driven member and the driving connection and adapted to establish contact therewith and so constituted that the areas in contact of the interposed element and the driving connection will remain approximately constant while passing from an engaged to a disengaged position, and means whereby the driving connection will automatically become ineffective.

8. In a device for starting engines and the like, in combination, a power member constituting the driving means, a driven member, a normally effective positive driving connection therebetween comprising a clutch member adapted to engage the driven member, normally engaging contact surfaces on the clutch member and on the driven member, means for automatically releasing the clutch member and means comprising a roller between said contact surfaces whereby the areas in contact are maintained at approximately their initial area while passing from an engaged to a disengaged position.

9. A demeshing device comprising a driving member, a latch pivoted thereto, a driven member having a driving face adapted to engage a driving face on said latch by means of an interposed roller and inertia means for moving the driving face of said latch away from contact with said roller. 5
10. In the art of disconnecting a driving from a driven means, a latch pivoted to the 10 driving means for demeshment from the driven means and having a face concentric with the pivot point of said latch, a corresponding face on the driven means, and a flexibly held roller interposed between the 15 two said faces whereby a sliding contact between the faces during the demeshing movement is eliminated. 70
11. A back fire release device including a crank handle, a latch pivoted thereto, a 20 driven disk, a notch in the periphery therewith of and a roller in said notch adapted to engage said latch and to afford rolling contact therefor and means for retracting the latch from contact with the said roller. 75
- 25 12. In a device for cranking engines and the like, in combination, a hand crank, an inertially controlled latch pivoted thereto, a driven member having a notch normally engaged by said latch through the intermediary of an interposed roller in said notch, means adapted to effect a disengagement of the latch, and with the driven means except under conditions of relatively low 80 velocities therebetween. 80
- 30 13. In apparatus of the class described, in combination, a driving means, a driven means, a latch coacting with a roller to engage and disengage said means, and means comprising said latch and roller whereby engagement is only possible at low relative 85 speeds between the driving and the driven means. 90
- 35 14. In apparatus of the class described, in combination, a driving means, a driven means, a latch on the driving means engaging a roller on the driven means, said latch releasing the driven means under a sudden reversal of said driven means and so constituted as to re-establish the driving connection only when the relative speed between 95 the driving and the driven means is low. 100
- 40 15. In apparatus of the class described, in combination, a driving means, a driven means, an automatically severable connection therebetween comprising a roller 105 adapted to move with a latch to a disengaging point and means to prevent the re-engagement of the parts while the driven means is rotating with substantial velocity 110 relative to the driving means. 115
- 45 16. In a device for disconnecting a driving from a driven member, in combination, a roller interposed between driving faces on the driving and driven members respectively, and a releasing member adapted to move with 120 said roller to a disengaging point, and means associated with said releasing member whereby its driving face may be retracted from engagement with said roller to effect a severance of the driving connection. 125
- 50 17. A device for disconnecting a driving from a driven member comprising, driving faces on the driven and driving members respectively, means on one member whereby its driven face may be moved from engagement, 75 an anti-friction roller interposed between said driving faces, the driving faces being disposed with their surfaces substantially normal to the direction of load between them whereby reactions from said driving load which would tend to cause disengagement are eliminated. 80
- 55 18. In apparatus of the class described, a driving means and a driven means, an engaging portion on the driving means, a latch having an engaging portion and adapted to engage the driven means through the intermediary of an interposed roller adapted to minimize wear of the engaging portions. 85
- 60 19. In apparatus for severing the connection between driving and a driven means, a latch on the driving means, an engaging face on the driven means, and a roller interposed between said latch and said driving face to minimize friction, and means for operating said latch in and out of engagement with 95 said roller. 95
- 65 20. In the art of disconnecting a driving from a driven means while under load, a fulcrum on the driving means, a latch pivoted thereon and having a driving face concentric with said fulcrum, a corresponding face on the driven means also concentric with said fulcrum when the parts are in engaged relation and a resiliently retained roller between said concentric driving faces the whole organized so as to sever the driving connection on suitable movement of said latch. 100
- 70 21. In the art of severing the connection between a driving and a driven member, driving faces on the driven and driving members respectively coacting with an interposed anti-friction roller whereby disengagement may be effected without sliding friction, and inertia means for effecting said disengagement. 110
- 75 22. In the art of severing the connection between a driving and a driven member, driving faces on the driven and driving members respectively demeshably coacting with an interposed anti-friction roller whereby excessive wear of the said driving faces due to demeshing under full load is avoided, and means independent of an anchorage for producing said demeshing. 120
- 80 23. In apparatus of the class described, a driving means, a driven means, a latch adapted to form a severable driving connection 130

tion between said means, a roller interposed between the latch and one of said means for the minimizing of wear of the engaging parts.

24. In the art of severing a driving connection between a driving and a driven member, in combination, a driving face in the driven member, a roller flexibly held thereagainst, a latch adapted to engage said roller, and means for withdrawal of said latch from contact with said roller.

25. In a detachable cranking handle for starting engines and the like, in combination, a driving and a driven member, a normally operative severable driving connection therebetween comprising a roller and a latch thereagainst, means for automatically severing said driving connection upon retraction of the latch from the roller by a sudden adverse rotation of the driven member and means whereby the driving connection is automatically restored to an operative position when the relative speed of the driven and the driving members is low.

26. In a device for manually rotating a drive shaft to start an engine, in combination, a driving member, a driven member, means on the driven member to engage the drive shaft to rotate the same, a normally operative driving connection between the driving and the driven member comprising a latch, a notch and a roller resiliently held in said notch, means for automatically severing said driving connection when the rotation of the drive shaft becomes opposed to that of the driven member and means whereby the driving connection is automatically restored to an operative position when the relative rotational speed of the driven and the driving members is low.

27. In a device of the class described, the combination with an internal combustion engine having a drive shaft, of a driving member, a driven member loosely mounted on the drive shaft in a manner to engage the same for rotation, a normally operative driving connection between the driving and the driven member comprising a means engaging an anti-friction member, means for automatically severing said driving connection when the rotation of the drive shaft becomes opposed to that of the driven member, and means whereby the driving connection is automatically restored when the driving manner is normally rotated.

28. In a device of the class described, in combination, a hand crank constituting the driving means, a driven means adapted to be secured to an engine shaft, the driven means mounted for rotation in the driving means, a notch in the driven means, a roller flexibly held in said notch, a latch pivoted

on the driving means adapted to engage the roller, a spring means to normally keep the latch in an engaged position, a weighted lever adapted to assist said spring means in maintaining the latch in engaged position when the hand crank is normally operated, said weighted lever further adapted to effect a release of the latch when the hand crank is abnormally rotated and a counter-balance for said weighted lever.

29. In a device of the class described, in combination, a driving means, a driven means, a severable driving connection therebetween comprising a notch a roller and a latch, said driving connection adapted to be maintained in an operative position when the driving means is normally rotated and to be moved into an inoperative position when said driving means is abnormally rotated and means whereby the driving connection is adapted to form a drive in either a clockwise or a counter-clockwise direction as desired.

30. In a device of the character described, the combination of a driving member, a driven member, a pawl associated with the driving member engaging a roller associated with the driven member in a manner so as to normally form a driving connection between said driving and driven members, said pawl and roller so constituted as to minimize friction in a releasing action.

31. In a device for starting engines and the like, the combination of a driving member, a driven member, a normally effective positive driving connection comprising a latch therebetween, an interposed element associated with the driven member and the driving connection and adapted to establish contact therebetween and so constituted that a sliding contact of the parts when disengaging is eliminated, and means responsive to a deceleration of the driving means for actuating said latch.

32. In a device for starting engines and the like, the combination of a driving member, a driven member, a normally effective positive driving connection comprising an inertially controlled latch therebetween, an interposed element associated with the driven member and the driving connection and adapted to establish contact therebetween and so constituted that a movement from an engaged to a disengaged position will be made by a rolling action of the surfaces.

Signed at Keyport in the county of Monmouth and State of New Jersey this 18th day of November, A. D. 1922.

ROLAND CHILTON.
ALEXANDER H. KING.
